US00D708231S

(12) **United States Design Patent**
Niakan et al.

(10) **Patent No.:** US D708,231 S
(45) **Date of Patent:** ** Jul. 1, 2014

(54) **AUTOMOTIVE AIR INTAKE SYSTEM**

(71) Applicants: **Shahriar Nick Niakan**, Anaheim Hills, CA (US); **Christian Luc Landel**, Corona, CA (US)

(72) Inventors: **Shahriar Nick Niakan**, Anaheim Hills, CA (US); **Christian Luc Landel**, Corona, CA (US)

(73) Assignee: **Advanced Flow Engineering, Inc.**, Corona, CA (US)

(**) Term: **14 Years**

(21) Appl. No.: **29/442,578**

(22) Filed: **Mar. 26, 2013**

(51) LOC (10) Cl. **15-05**

(52) U.S. Cl. **D15/5**
USPC .....

(58) **Field of Classification Search**

USPC ....., D15/1-5; D12/194, 400; 123/184.21,
123/184.46

See application file for complete search history.

(57) **CLAIM**

The ornamental design for an automotive air intake system, as shown and described.

DESCRIPTION

FIG. 1 is a view of the top side of an automotive air intake system showing my new design;

FIG. 2 is a back view of an automotive air intake system showing my new design;

FIG. 3 is a left side view of an automotive air intake system showing my new design; and,

FIG. 4 is a perspective view of an automotive air intake system showing my new design.

1 Claim, 4 Drawing Sheets
